Primary Examiner—Alan P. Douglas*Assistant Examiner*—Cathron B. Matta*Attorney, Agent, or Firm*—Birch, Stewart, Kolasch & Birch[57] **CLAIM**

The ornamental design for a planter, as shown and described.

DESCRIPTION

FIG. 1 is a left side elevation of the planter, the right side view being a mirror image thereof;

FIG. 2 is a top perspective view of a flower vase; and, FIG. 3 is a front elevation of the planter, the rear elevation being a mirror image thereof.

The bottom surface of the flower vase is flat and plain, except for the four semi-spherical feet.
